UNITED STATES PATENT OFFICE.

ANDREW S. FISHER, OF BEDFORD, PENNSYLVANIA, ASSIGNOR OF ONE-HALF
TO MILTON H. VALENTINE, OF SAME PLACE.

SASH-FASTENER.

SPECIFICATION forming part of Letters Patent No. 483,837, dated October 4, 1892.

Application filed June 22, 1892. Serial No. 437,594. (No model.)

To all whom it may concern:

Be it known that I, ANDREW S. FISHER, a citizen of the United States, residing at Bedford, in the county of Bedford and State of Pennsylvania, have invented a certain new and useful Improvement in Window Lifts and Locks, of which the following is a full, clear, and exact description.

The object of this invention is to provide means for readily raising and lowering window-sashes and locking them in any given position, and at the same time and by the same means tightening such sashes in their frames, so as to minimize, if not entirely overcome, rattling or clattering.

My invention is designed, primarily, for railway-car windows where there is very apparent necessity for easily-operated window-sashes and for sashes that will exclude dust and the elements.

Having thus described the principle of my invention, I will proceed now to set forth in detail the best mode in which I have contemplated applying that principle, and will then particularly point out and distinctly claim the part, combination, or improvement which I claim as my invention.

In the accompanying drawings, illustrating my invention, in the several figures of which like parts are similarly designated, Figure 1 is a partly-sectional elevation. Fig. 2 is an elevation looking toward Fig. 3 from the left; Fig. 3, a partly-sectional side view; and Fig. 4 is an elevation looking toward Fig. 3 from the right. Fig. 5 is a partly-sectional elevation of the lift, and Fig. 6 is a vertical section of the parts shown in Fig. 5.

I will describe my invention as applied to a railway-car window, but do not thereby intend to be understood as limiting its use and applicability to such windows.

a is the frame, and *b* the sash, both of which may be and are hereshown as of ordinary construction and arrangement, excepting as hereinafter described. The frame is supplied at opposite sides with a double-faced rack-bar *c*, having teeth or cogs *c'* and *c''*, (see Figs. 1, 3, and 4,) arranged at right angles to one another. The sash also on opposite sides is mortised at *d*, and this mortise is covered on its edge by a metal plate *e*, which is provided with

cheek-pieces *e'*, which receive and support the arbor *e''* of a toothed wheel *e'*, the teeth of which project through an opening in plate *e* and engage the cogs *c'* of the rack-bar. This wheel is supplied with an internal coiled spring *e''*, Fig. 3, the outer end of which is made fast to the wheel and the inner end to the arbor, so that as the sash is lowered the spring will be wound up or put under tension by the rotation of the wheel, consequent upon its engagement with the rack-bar, and therefore spring-power will be stored or accumulated by the descent of the sash, to be utilized thereafter for assisting in raising the sash when that is desired. These spring-wheels, hence, take the place of sash-weights and become sash-balances. An eccentric lever *f* is pivoted on the plate *e* in such relation to the teeth of wheel *e'* as to be capable of engaging such teeth, and thereby locking the wheel against reverse rotation when under tension and while the sash is being placed in the frame. In the plate *e* is made a longitudinal slot *g*, Figs. 2 and 4, and below this slot and on the outer face of the plate is pivoted a dogging device *h*, having a foot *h'*, which engages the cogs *c''* to support the sash in any given position and for a further purpose presently appearing. This dogging device is provided with an oblique slot *h''* opposite the slot *g*. A rod *i* has its upper end arranged back of the plate *e* and terminates in a hook *i'*, which projects through the slots *g* and *h''*. A spring *j* is coiled about this rod and fastened to it at one end, while its other end abuts against a projection *j'* on the plate *e*, the stress of said spring tending normally to raise the said rod, and thereby throw the foot *h'* into engagement with the cogs *c''*, and not only so, but to force the sash against the window-strips, and so make it fit tight, and thus prevent or reduce rattling or clattering and also exclude dust and the elements.

The rods *i* on opposite sides of the sash extend toward the bottom rail of the sash and are there secured to a transverse bar *k*, which is arranged in a groove *l* in the said rail. To this bar is secured a push-piece *m* by which the bar is depressed, so as to draw down the rods *i* and thereby vibrate the dogging devices *h* and release their feet from cogs *c''*, and so permit the

sash to be raised and lowered. Instantly the depression of the bar *k* ceases the springs *j* elevate the rods *i* and cause the dogging devices to return to engagement with the cogs *c*². A casing *n* supports the push-button *m* and subserves the additional purpose of a lift for the sash.

Obviously, instead of applying the toothed wheels in mortises in the sash, they may be placed outside of them, and by further rearrangement of parts the racks and the wheels and their appurtenances might change places on the window.

By this invention I provide a sash hoisting, locking, and tightening device, which may be readily operated by one hand and which obviates the tugging and exertion commonly necessarily put forth in operating window-sashes as usually constructed.

20. What I claim is—

1. An improved window-sash hoisting, locking, and tightening device consisting of two pivoted dogging devices having oblique slots in one end and feet on the other end, stationary plates having straight longitudinal slots therein intersecting the oblique slots of the dogging devices, toothed racks engaged by said dogging devices, rods connected by hooks *i'* at one of their ends with said dogging devices through said slots and attached at their other ends to the ends of a rigid bar extending across the bottom edge of the sash, springs fastened to said rods and bearing against abutments on the stationary plates normally to raise said rods and throw and hold the dogging devices in engagement with the toothed

racks, and a push-piece attached to said bar and adapted to operate said dogging devices through the bar and rods, to unlock, release, and loosen the sash, and also to permit said dogging devices to lock and tighten it, in combination with sash-balancing devices, such as spring-toothed wheels, adapted to engage the toothed racks, substantially in the manner and for the purpose set forth. 40

2. An improved window-sash balancing, hoisting, locking, and tightening device comprising a balancing medium, preferably coiled springs incased in hollow toothed wheels which are held in position in the sash or frame by suitable cases, face-plates on such cases having straight longitudinal slots and toothed racks or plates adapted to engage and turn said toothed wheels, a flat movable cross-bar, a push-piece attached thereto, and rods connected to such cross-bar and fitted with spiral springs and having hooked ends *i'* passed through said straight slots in said face-plates and through oblique slots in dogging devices pivoted to said face-plates, the other ends of said dogging devices being provided with feet to engage the racks, whereby the sash can by one hand be raised, stopped, locked, and tightened or loosened and released at any desired position, in the manner described, and substantially as and for the purposes set forth. 55

In testimony whereof I have hereunto set my hand this 18th day of June, A. D. 1892.

ANDREW S. FISHER.
